UNITED STATES PATENT OFFICE

THOMAS A. DICKS, OF PITTSBURGH, PENNSYLVANIA, ASSIGNOR TO PITTSBURGH SCREW AND BOLT CORPORATION, OF PITTSBURGH, PENNSYLVANIA, A CORPORATION OF PENNSYLVANIA

REINFORCED PROPELLER BLADE END

Application filed September 19, 1929. Serial No. 393,672.

This invention relates to propeller blade ends and more particularly to tubular propeller blade ends which are inserted into hubs containing angular sockets for the reception 5 of the blade ends and wherein the blade ends are strengthened so as to provide a strong efficient connection with the hub socket.

As I have disclosed in other of my applications it is customary to provide a hub having 10 angularly disposed sockets therearound for the reception of the ends of the propeller blades such as those used for aeronautical purposes or for other similar or analogous purposes. In these other inventions I have 15 strengthened the connection between the propeller blade end and its socket by welding metallic inserts to the interior surfaces of the propeller blade end at diametrically opposite points thereof, but I have found that 20 it is somewhat difficult and inconvenient to make these welds as they are comparatively inaccessible and hence difficult to finish smoothly and properly. The strength of the weld is, therefore, not as great as might be 25 obtained were the weld performed in a more accessible location and hence the speed with which the welds can be completed is relatively slow and thus the cost increased.

It is an object of the present invention, 30 therefore, to strengthen the connection between the propeller blade end and the hub socket in a more accessible and inexpensive manner.

It is another object of the present invention to make the reinforcement on the exterior surface of the propeller blade end 35 rather than on the interior surface.

It is a further object of the invention to flatten or depress suitable and preferably 40 diametrically opposite portions of the propeller blade end and to use the depressions thereby formed in which to accomplish the reinforcement.

Other and further objects of the invention 45 will either be apparent hereinafter or will be pointed out as the description proceeds.

I have illustrated two forms of my invention in the accompanying drawings where- 50 in;

Figure 1 is a plan view of the end of the tubular propeller blade.

Fig. 2 is a section on the line II—II of Fig. 1.

Fig. 3 is a section on the line III—III of Fig. 1 and;

Fig. 4 is a view similar to Fig. 3 of a modified form of the invention.

Similar numerals refer to similar parts throughout the several views.

Referring now in detail to the drawings, the end 10 of a propeller blade has a wall 11 and the blade is shown tubular, although conceivably it might be otherwise. At the shank end of the tubular blade where it is inserted into a socket in a hub (not shown) the shank is flattened or depressed as shown. The depth of the depressions is substantially the thickness of the wall 11 of the propeller blade, although the exact depth of the depressions can be suitably adjusted or determined according to the reinforcement required and any other circumstances affecting or limiting the various sizes and proportions involved.

The form and shape of the flattened or depressed portions is clearly understood by a reference to Figs. 2 and 3 and from which it will be seen that each depression has a flat floor 12 and inclined or sloping walls 18, the whole depression being relatively shallow and, as shown, approximately the depth of the blade wall 11. In the form shown, it is apparent that two such depressions have been 80 formed at diametrically opposite points and centrally of each depression is a polygonal aperture 14 through which a cross bolt (not shown) passes when the blade end is inserted into the socket of a suitable hub (also not shown).

In order to reinforce the shank end at the portions where the depressions are made, since the cross bolt passes therethrough and requires reinforcement at those points, a reinforcing metal insert 15 for each depression is provided which has a flattened bottom 16, but the upper surface 17 of which is contoured or configured so that it, at least in part, restores the original outline of the blade 90 95 100

end. This insert 15, in the form illustrated, is circular, but it is clear that an insert of any other suitable or required shape might be equally well used. As will be noted the 5 metal inserts are smaller than the depressions formed and generally fill up substantially only the central and deepest portion of the depressions, leaving around the metal inserts a substantially triangular groove, which 10 is thereupon filled by weld or solder 18 in order to completely restore the original contour to the exterior surface of the blade end at the depressed portions. This weld 18 firmly and completely unites all the contiguous 15 portions and the result is that the finished propeller blade end is stronger and more unitary than ever and hence a greatly strengthened end is provided. The apertures 14 in the depressions and those 19 in the metal 20 inserts are congruent and register completely and smoothly so that a cross bolt can be inserted as if in an unchanged blade end.

Since the operations are carried out on the exterior surface of the blade end instead 25 of on the interior surface the work can be economically, speedily and perfectly performed, giving a smooth, firm construction, which is rigid and which will completely fulfill the 30 functions for which it was designed.

It is clear that the size and shape of the 35 metal inserts 15 may be proportioned and contoured as found most efficient and satisfactory and it may be desirable to form the insert with the sides thereof inclined rather than straight, as shown, and such incline may be in either direction so that the largest circumference will occur either at the top or in the bottom surfaces, which may have the additional function and effect of holding the 40 weld or solder 18 more firmly in position.

In the modification shown in Fig. 4 a very simple and very effective form of the invention is illustrated. In this modification the 45 depressions are formed similarly to the depressions referred to in Figures 1, 2 and 3, but instead of filling the depressions partially with metal inserts these depressions are entirely filled with weld or solder 20 except, of course, the central portion which is 50 left with an aperture 21 congruent to and registering with the apertures 14 in the floor of the depressions. This form has the advantage of extreme simplicity and rapid accomplishment in conjunction with less expense, so that unless an extremely strong and rigid construction is required, I may utilize 55 the form of the invention shown in Fig. 4.

It is, of course, to be understood that all 60 the above is intended to be illustrative and not limitative, and that I may still further vary and modify the details without departing from the spirit and scope of the invention. The size and shape of the depressions 65 may be varied, the size and shape of the metal

inserts may be varied and the size and shape of the apertures provided are variable to conform with the shape and size of the cross bolt to be inserted therethrough. It is further to be understood that the diameter of the propeller blade may be any desired one and that the thickness of the walls is conformable to the size of the blade. The slope of the depression walls may be any desired or may be undercut by sloping them in the 75 opposite direction to that shown.

Although I have shown all the parts as being metallic, it is possible that other materials could be substituted where the requirements of use permit the same, and although I have particularly referred to the aeronautical field it is clear that the invention may be applied to the marine field or to any other field of endeavor in which the above principles can be utilized to advantage.

What I claim as new and desire to secure by Letters Patent is:

1. A detachable tubular propeller blade having a shank end provided with transversely extending diametrically opposite exterior depressions and metallic reenforcements in said depressions restoring the original undepressed contour of the shank end of the blade.

2. A tubular propeller blade shank having diametrically opposite exterior depressions with a flat floor and sloping sides, and a metallic reenforcement with a flat bottom in each depression, the opposite surface of the reenforcement restoring the original contour to at least a portion of the depressed blade shank, the original contour being completed by weld.

3. A tubular propeller blade shank having diametrically opposite depressions of a depth approximately the thickness of the blade shank wall, each depression having a flat floor and sloping sides, a metallic reenforcement in each depression having a flat bottom resting on the flat floor of the depression, the top of the reenforcement and the added weld completely filling said depressions and restoring the original exterior contour of the blade shank.

4. A tubular propeller blade shank having diametrically opposite exterior depressions provided with a flat floor and sloping sides and a central aperture passing therethrough, a metal insert having a flat bottom resting on the flat floor of the depression, and having a top surface contoured to complete at least in part the original contour of the blade shank, the remaining space in the depression being filled with weld, so configured on its upper surface as to complete the original exterior contour of the blade shank as it existed before the formation of the depressions.

5. A tubular propeller blade shank hav-

ing diametrically opposite exterior depressions provided with a flat floor and sloping sides and a central aperture passing therethrough, a metal insert having a flat bottom resting on the flat floor of the depression, and having a top surface contoured to complete at least in part the original contour of the blade shank, the remaining space in the depression being filled with weld, so configured on its upper surface as to complete the original exterior contour of the blade shank as it existed before the formation of the depressions, said metal insert having a central aperture congruent to and registering with the aperture in the floor of the depression.

5 6. A detachable tubular propeller blade having a shank end provided with transversely extending diametrically opposite depressions and welding metal in said depressions for reenforcing said shank and for restoring the undepressed contour of the shank.

20 7. A detachable tubular propeller blade having the shank end provided with transversely extending oppositely disposed exterior depressions, said depressions having a flat floor, sloping side walls extending transversely across the shank, an aperture through the center thereof and a metallic weld in said depressions having an aperture therein registering with the aperture in said depressions for reenforcing the shank end of said blade.

25 In testimony whereof, I have hereunto subscribed my name this 18th day of September, 1929.
